UNITED STATES PATENT OFFICE.

ROBERT F. SNYDER, OF TOLEDO, OHIO, ASSIGNOR OF ONE-HALF TO WILBER A. OWEN AND CHARLES W. OWEN, OF TOLEDO, OHIO.

CLEANER FOR SIEVES.

SPECIFICATION forming part of Letters Patent No. 711,133, dated October 14, 1902.

Application filed June 26, 1902. Serial No. 113,247. (No model.)

To all whom it may concern:

Be it known that I, ROBERT F. SNYDER, a citizen of the United States, residing at Toledo, in the county of Lucas and State of Ohio, have 5 invented certain new and useful Improvements in Cleaners for Sieves; and I declare the following to be a full, clear, and exact description of the invention, such as will enable others skilled in the art to which it appertains 10 to make and use the same, reference being had to the accompanying drawings, and to the figures of reference marked thereon, which form a part of this specification.

My invention relates to improvements in 15 cleaning devices for all screens or sieves used in the separating or cleaning of grain, flour, or other fine substance which have a rotary, a semirotary, or a reciprocating motion, but is more particularly adapted for use on cloth 20 sieves or screens employed in grist or flour mills. It consists of the novel features, details of construction, and combination of parts, which hereinafter will be more fully described and finally claimed.

25 The object of my invention is to provide, first, a simple, cheap, and effective screen or sieve cleaner, by means of which the screen or sieve may while in operation constantly be kept free from the filling up and clogging there- 30 of incident to the nature of their use and which so impede the class of work to which they pertain; second, a device to perform the purpose described which is so arranged, con- 35 structed, and capable of adjustment as to prevent the tearing or wearing of holes in the cloth or screen and the racking of the frame, the faults found to be present in the various devices now in use for that purpose; third, a cleaner which may be readily adjusted to a 40 light or heavy stroke of the arms against the screen or sieve, and, fourth, a cleaner which carries its own actuating means, the same being actuated by the motion imparted to the screen or sieve, and thus making its opera- 45 tion not dependent upon a separate and distinct mechanism.

While the essential and characteristic features of the invention are necessarily sus- ceptible of modification, still the preferred

embodiment thereof is illustrated in the accompanying drawings, in which—

Figure I is a perspective view of a sieve or screen having the cloth or wire-netting partly cut away and showing the same as provided with my invention and the means by which it is supported beneath the sieve and its method of adjustment. Fig. II is a vertical sectional view of my device and the sieve to which it is attached, showing the ball or sphere in the tubulous portion of the same.

In the drawings, 1 represents the frame or main portion of the sieve or screen with the cloth or wire-netting 2 stretched across the top surface thereof, beneath which is secured my invention by means hereinafter more specifically referred to and described.

The body or main portion 3 of the device with which I perform the objects above enumerated is cylindrical and circular in form and is provided with the radially-projecting 70 arms 4, extending on a horizontal plane with the cylindrical body 3. Referring to Fig. II, it will be noticed that the said cylindrical body 3 is composed of two annular parts, the upper portion 3' and the lower portion 3" of the body 3. Each of the annular parts 3' and 3" is concavo-convex in shape, so that when they are placed together they conjointly form a hollowed-out annular or tubulous body, as shown at 5. These semitubular parts 3' and 3" may be provided on their inner surfaces with the annular flanges 6 and 6', formed integral with said parts and having a series of apertures 7 therein or with lugs or ears like- 75 wise provided with apertures, the apertures in the flanges or lugs of the lower part 3" being internally screw-threaded to permit of the said parts 3' and 3" being bound together by the insertion of the screws 7' in the said apertures. Integral with the said part 3' and 80 extending diametrically across the same is the bridge 8, having the upright portion 8', which is provided with the aperture 8" for the insertion of the shaft or wire 10. The radial arms 4, which are made integral with the 85 part 3', are provided at their outer ends with the dovetailed grooves 4', in which are inserted and securely fixed the knockers 4",

said knockers being made of rubber or other fungible substance. I prefer a substance of this character to prevent the tearing or mutilating of the sieve cloth or screen.

5 For the actuating means of my said invention I provide a ball or sphere 9, which is loosely placed within the circular chamber 5, formed in the member 3, which is caused by the rotary, semirotary, or reciprocating motion of the sieve or screen to rotate within the said member or body 3.

To support my said invention and hold it in proper adjustment to the screen or sieve, I provide a shaft or wire 10, which may be extended either longitudinally or transversely of the frame 1, said shaft or wire being supported at either end by the plates 11, which are rigidly attached to the frame by means of a bolt being inserted in the elongated slot 12 and passed through an aperture in the frame and either secured on the opposite side by a nut or be engaged with threads on the interior of the aperture. At one end of the plates 11 is formed a journal or enlarged portion 13, with the socket 13' therein, as shown, in which the shaft or wire 10 loosely rests, thus permitting my device, which is rigidly hung thereon by reason of the shaft or wire 10 extending through the aperture 8" of the bridge 8, to have a rocking or oscillating motion, said motion being caused by the ball or sphere 9 rotating within the member 3. The elongated slots 12 are provided in the plates 11 to permit of the adjustment of the said cleaner with relation to the sieve or screen 2 by raising or lowering the wire or shaft 10 when it is desired to have a weaker or stronger stroke of the arms 4. I wish it understood, however, that I do not confine myself to this means of supporting and adjusting the said cleaner, as the same result may be accomplished by numerous other methods.

In operation as many of my said cleaners as are desired may be slipped over the wire or shaft 10 and rigidly secured thereon at suitable distances apart. The ends of the wire or shaft 10 are then inserted in the sockets 13' of the plates 11, which are rigidly secured to the frame, and allowed to rest loosely therein. As the motion imparted to the sieve or screen is of a jerky or gyratory nature and very rapid, the ball or sphere 9 within the annular channel 5 is caused to move rapidly around the same. The sphere 9 is of sufficient weight to overpower the equilibrium of the member 3 as it hangs on the shaft 10 and to impart an oscillating motion to the said member as the sphere is carried by its own weight and momentum rapidly around the channel 5 from one side of the shaft 10 to the other, thus causing the knockers 4" on opposite sides of the fulcrum-point or shaft 10 to alternately strike the cloth or screen 2 with sufficient force to keep the meshes of the same open and free of the substances which

would otherwise collect and accumulate therein when in operation. The force and length of the stroke of the arms 4 may be readily regulated by raising or lowering the slotted plates 11.

Having thus described my invention, what I claim as new, and desire to secure by Letters Patent, is—

1. In a sieve-cleaning device, an annular body provided with a channel therein, a ball in said channel, radial arms projecting from said annular body, means for supporting said body, and means for adjusting said support with relation to the sieve. 75

2. In a sieve-cleaning device, a body provided with a channel therein, radially-projecting arms on said body, means for supporting said body, said means consisting of a shaft secured to the sieve, and means for oscillating said body with said shaft as a fulcrum. 80

3. In a sieve-cleaning device, a wire attached to a sieve, a body provided with a channel suspended from said wire, arms projecting from said body, a ball in said channel and adapted to rotate within the same. 90

4. In a sieve-cleaning device, a body adapted to be held in close proximity to a sieve, a movable element held in engagement with said body and adapted, when motion is imparted to said sieve, to move rapidly from one side of said body to the other and cause the extremities of said body to alternately come in contact with the sieve. 95

5. In a sieve-cleaning device, the combination with a sieve, of a hollow, annular body, a ball in said hollow body and adapted to rotate within the same, arms projecting radially from said body, a wire adjustable on said sieve and adapted to support the said body. 100

6. In a sieve-cleaning device, the combination with a sieve-frame having a covering thereon, of a body comprising upper and lower concavo-convex parts and adapted to conjointly form a tubular body, means for securing said parts together, radially-projecting arms on one of said parts, means attached to the frame for loosely supporting said body, and means to impart an oscillating motion to the same. 110

7. In a sieve-cleaning device, the combination with a sieve, of a body, a ball within said body, radially-projecting arms on said body, said arms being enlarged at their outer extremities, means attached to the sieve-frame for supporting said body, said means comprising a shaft and plates secured to frame to support said shaft, and means for adjusting the said shaft. 120

8. In a cloth-cleaner for sieves, the combination with a sieve, of a body provided with a hollow portion, said body comprising two concavo-convex parts, means for joining said parts, a bridge having an aperture therein extending transversely of one of said parts, 125

radially-projecting arms on one of said parts, a ball in said body and adapted to rotate within the same, and means for supporting said body and holding it in close proximity to said 5 sieve, said means comprising a wire extending parallel with said sieve and attached to same by plates secured to frame thereof.

In testimony whereof I have signed my name to this specification in the presence of two subscribing witnesses.

ROBERT F. SNYDER.
